SCREENING DEVICE

Filed Nov. 1, 1918

UNITED STATES PATENT OFFICE.

BASIL B. CARLTON AND CLEM J. BURKLEY, OF AKRON, OHIO, ASSIGNEES TO THE GOOD-YEAR TIRE & RUBBER COMPANY, OF AKRON, OHIO, A CORPORATION OF OHIO.

SCREENING DEVICE.

Application filed November 1, 1918. Serial No. 260,739.

To all whom it may concern:

Be it known that we, BASIL B. CARLTON and CLEM J. BURKLEY, citizens of the United States, and residents of Akron, Ohio, have invented new and useful Improvements in Screening Devices, of which the following is a specification.

Our present invention relates to screen construction; and more particularly to the construction of screens of the class which, in operation, are mechanically jarred to render them more effective in their action of separating finely divided materials.

By reason of the bending and vibration to which they are subjected in operation, the mechanically jarred wire screens of screening machines are likely to be weakened and broken after they have been in service for a comparatively short period of time. The weakness and breaks usually develop and occur near that portion of the wire screen where the sharp blows delivered to the rigid bars are immediately transferred to the flexible wire screen, causing a quick and sudden bending or flexing. The breaks also occur where the flexible screen is fastened to the rigid frame and where the vibration passes out of the movable screen into the stationary frame.

To prevent the weakening and breaking of the wire screen in use is the principal object of our invention, and we propose to strengthen and reinforce it by means of a flexible substance, such as vulcanized rubber material, incorporated into and on both sides of that portion of the wire screen where cracking and breaking is most liable to occur. The flexible material so incorporated in the wire screen is adapted to distribute over a large area the effects of the bending of the wire screen, and it acts to save the wire screen from the destructive effects of the vibration and bending.

The above and additional objects of a similar nature, which will be hereinafter more specifically treated, are preferably accomplished by such means as are illustrated in the accompanying drawings, described in the following specification, and then more particularly pointed out in the claims which are appended hereto and form a part of this application.

With reference to the drawings, wherein there has been illustrated a preferred embodiment of the invention, and throughout

the several views of which, similar reference numbers designate corresponding parts:

Figure 1 is a plan view of a wire screen or gauze having my invention applied thereto;

Figure 2 is an end view of the same; and

Figure 3 an enlarged sectional view taken on line 3—3 of Figure 1.

The frame 11 of the wire screen or gauze 10 and its mounting, as well as the jarring mechanism of the screening machine, may be of any suitable form as they constitute no essential part of the present invention.

In carrying out our invention we propose to incorporate along the middle and marginal edge portions of the wire screen a web of flexible material 12. This web may be of any suitable material but we preferably employ a rubber compound applied in sheets 75 upon both sides of the screen and vulcanized. This causes the compounds to run and penetrate the interstices of the screen and unite the two sheets together as will be understood.

In case the jarring mechanism includes the usual steel bar 14 having thereon projections 15 which are intermittently struck by tappets, (not shown), or the like, the bar 14 is preferably disposed along the middle portion of the web 12 and a strip or mat 16 of cotton or other suitable fabric is interposed between these two elements as clearly shown in Figs. 2 and 3 of the drawings. The bar 14 may be secured in place by any suitable means, that shown consisting of a metal strip 18 placed on a mat 19 of fabric. This latter element is arranged on the face of the web 12 opposite to the face on which the mat 16 and the bar 14 are positioned. A plurality of small bolts 20, pass through the elements 18, 19, 12, 16, 14 and are provided with washers 21 and clamping nuts 22 for effectively clamping all of the elements together.

We have also found it practical and expedient to reinforce in a like manner the marginal edge portions of the screen, as shown at 23, particularly along the edge portions gripped or engaged by the frame 103 forming the support for the entire screen. Here too the vibration and strains are experienced, only in a manner reversed from the middle section, as, in this instance the vibrations are transferred from the flexible

screen to a stationary member, while in the center the vibrations are passed out from a rigid member (the tappet bar) to the flexible screen.

5. It will be seen that the simple expedient of providing the web 12 of flexible material on the wire screen 10, greatly prolongs the life of the wire screen in service and it is to be understood that other materials and arrangements other than those shown and described may be used without departing from the spirit of my invention, or from the scope of the appended claims.

What we claim is:

15. 1. A device for separating finely divided material comprising a screen partially supported by and embedded in a flexible material.
2. A screen for separating finely divided material, provided with a rubber compound incorporated therein for the purpose set forth.
3. A screen for separating finely divided material, having a web of flexible material along its middle portion for the purpose set forth.
4. A screen for separating finely divided material, having a web of vulcanized rubber material incorporated in the middle portion of the screen for the purpose set forth.
5. A screen for separating finely divided material, having a web of flexible material along its middle portion, and having its

marginal edge portions reinforced with vulcanized rubber material.

6. A screen for separating finely divided material, having a web of vulcanized rubber material incorporated in the middle portion of the screen, and having vulcanized rubber material incorporated in the edge portions of the screen.

7. A screen for separating finely divided material having means incorporated therewith for absorbing the vibration comprising oppositely disposed strips of vulcanizable material arranged intermediate the edges of the screen, said strips being vulcanized together to imbed the screen therein.

8. A screen for separating finely divided material having means for absorbing the vibration incorporated therewith comprising oppositely disposed strips of vulcanizable material arranged intermediate the edges of the screen, said strips being vulcanized together to imbed the screen therein, and a metallic strip superposed upon one of said strips in fixed relation thereto.

In witness whereof, we have hereunto signed our names in the presence of two subscribing witnesses.

BASIL B. CARLTON.
CLEM J. BURKLEY.
